MARTIN WHELAN, OF NEW HAVEN, CONNECTICUT.

Letters Patent No. 77,147, dated April 21, 1868.

IMPROVEMENT IN CARRIAGE-HUB.

The Schedule referred to in these Letters Patent and making part of the same.

TO ALL WHOM IT MAY CONCERN:

Be it known that I, MARTIN WHELAN, of New Haven, in the county of New Haven, and State of Connecticut, have invented a new Improvement in Carriage-Hubs; and I do hereby declare the following, when taken in connection with the accompanying drawings, and the letters of reference marked thereon, to be a full, clear, and exact description of the same, and which said drawings constitute part of this specification, and represent, in—

Figure 1, a perspective view of the hub,

Figure 2 a transverse section of one part of the band removed, and, in

Figures 3 and 4, the two parts of the band.

This invention relates to an improvement in the manner of securing spokes in carriage-wheels, the object being to sustain the spokes at the hub independent of the hub proper. This object has been partially attained by inserting the spokes into the hub, and constructing them so that the insides of the spokes meet each other a short distance between the spokes, and then by placing a band of metal around the face of the spokes on each side and bolting therethrough. Another method has been by placing a band around the hub, having mortises formed therein to receive the tenon of the spokes, and a shoulder on the spoke resting upon iron.

To the first there is this objection, that there is so large a body of wood entirely around the hub that a very slight shrinkage must open some of the joints, and thus detract from the advantage of the union of the spokes at the hub.

In the last construction there is this objection, that the spoke resting, as it does, upon a metallic shoulder, the slightest shrinkage tends to loosen the spoke, and when loosened in the slightest degree, the shoulder quickly wears so as to loosen the spoke.

By my invention these difficulties are entirely overcome, and consists in the construction of a band to encircle the hub, and inserting the spokes into the wood hub so as to leave a space between each two of the spokes; and upon the said band I form metallic bars, which pass through the several spaces between the spokes and a corresponding plate driven on to the hub upon the opposite side, and secured to the projecting arms upon the other plate, so that while the spokes are firmly secured into the wood hub, the bands are driven together through the spaces between the spokes, thus firmly binding and securing the whole together in the most perfect manner, and overcoming all the objections existing in other constructions.

To enable others to construct my improvement, I will proceed to describe the same as illustrated in the accompanying drawings.

A is a hub, constructed in the usual manner for carriage-hubs, and mortised to receive the spokes, as seen in fig. 2, so as to leave a space between each two of the spokes B B, and the spokes formed with a shoulder to set upon the surface of the hub, and the spoke made a little wider at the shoulder, and tapering from the shoulder up. C is a metallic band, formed to fit closely the spoke, and with projecting arms, a, corresponding to the spaces between each of the two spokes, as seen in figs. 2 and 3, and when the spokes are driven into the hub, then the plate C is driven on to the hub, and the several arms, a, enter the spaces between the spokes, and closely fill the said spaces, thus wedging the spoke into the hub, as the spoke, being thinner, at the upper surface of the arms than at the shoulder, the tendency of the metallic arms a is to force the spokes tighter into the hub.

More or less of the arms a, I furnish with a rivet, d, and upon the opposite side I force another plate, D, (seen in fig. 4,) being first perforated to correspond to the rivets d upon the plate C, and so that the said rivets pass through the perforations in the plate D, then head the rivets down on to the sail plate, securing the two plates together firmly against the spokes upon each side, or secure the two plates together in any equivalent manner.

I do not wish to be understood as broadly claiming providing a carriage-hub with metallic bands or plates to support the spokes, as this is not new, but

What I do claim as new and useful, and desire to secure by Letters Patent, is—

The plate C, provided with the arms or lugs a, combined with the hub A and spokes B and the plate D, when the whole are constructed and united, substantially in the manner herein set forth.

MARTIN WHELAN.
